MANUFACTURE OF NAPHTHALENE

Hibbard R. Emmerson, Santa Ana, Calif., assignor to Union Oil Company of California, Los Angeles, Calif., a corporation of California

Filed Sept. 29, 1961, Ser. No. 141,826
20 Claims. (Cl. 260—672)

This invention relates to an improved process for the manufacture of naphthalene, and in particular concerns an improved process for producing naphthalene by the dealkylation of alkylnaphthalenes.

The expanding use of naphthalene for the production of dicarboxylic acids useful in manufacturing synthetic resins and fibers has created considerable interest in the manufacture of naphthalene from petroleum hydrocarbons. It is well known that certain hydrocarbon fractions obtained in various petroleum refining operations, e.g., cracking and reforming, contain considerable quantities of alkylnaphthalenes which can be thermally or catalytically dealkylated to form free naphthalene. As such processes are conventionally carried out, a feedstock consisting of a reformate or cycle oil fraction boiling above about 430° F. and comprising alkylnaphthalenes, alkylbenzenes, alkyltetralins, alkylindanes, etc., is subjected to dealkylating conditions to obtain an effluent product which, after separation of normally gaseous materials such as hydrogen and low molecular weight hydrocarbons, is fractionally distilled to obtain: (1) a light gasoline fraction, (2) a naphthalene-containing fraction, and (3) a heavy fraction comprising unreacted alkylnaphthalenes which, after the removal of heavy ends and polymers, is recycled to the dealkylation zone. The naphthalene-containing fraction is then processed, e.g., by crystallization or fractional distillation, to isolate the naphthalene in substantially pure form, and the non-naphthalenic components are taken as process products useful as heavy gasoline blending stock.

The process of the present invention is based on my discovery that the non-naphthalenic products referred to above, i.e., those components of the naphthalene-containing fraction which remain after removal of the naphthalene therefrom, are capable of being reformed under conventional reforming conditions to obtain further amounts of naphthalene and alkylnaphthalenes which can be recovered and employed in the same manner as the naphthalene and alkylnaphthalenes produced in the dealkylation step. Thus, in a process of the type described above, in which the dealkylation feedstock is a heavy reformate fraction and the naphthalene is recovered from the naphthalene-containing fraction by crystallization, I have found that increased yields of naphthalene (based on the amount of feedstock charged to the reformer) can be obtained by recycling to the reformer the mother liquor obtained from the crystallization step. As will be apparent, the reformer to which the non-naphthalenic components of the naphthalene-containing fraction are passed need not necessarily be the one employed in preparing the dealkylation feedstock; it may be a reforming facility provided for the sole purpose of treating such components or it may be one located at a nearby or remote location and employed for a different purpose. In its broadest aspects, then, the process of the invention consists in subjecting an alkylnaphthalene-containing feedstock to dealkylating conditions to obtain a naphthalene-containing effluent, fractionating said effluent to obtain a naphthalene concentrate, separating substantially pure naphthalene from said concentrate, and subjecting the remaining components of the concentrate to reforming conditions.

In the accompanying drawings, FIGURE 1 thereof takes the form of a schematic flow diagram illustrating the process of the invention in its simplest embodiment.

2

FIGURE 2 likewise takes the form of a flowsheet, and illustrates a preferred embodiment. In the interests of simplification, such conventional process equipment as pumps, heat exchangers, reboilers, condensers, reflux lines, 5 phase separators, valves, instrumentation, have for the most part been omitted.

Referring now to FIGURE 1, the major items of processing equipment include dealkylation reactor 10, dealkylate phase separator 12, fractionation system 14, naphthalene purification column 16, reforming reactor 20, and reformate phase separator 22. The process feedstock, consisting of an alkylnaphthalene-containing cycle oil extract (B.R.=430°-485° F.) obtained by solvent extracting a cycle oil produced by the catalytic cracking of a Middle East crude, is introduced into the system via line 24 and passes to dealkylation reactor feed manifold 26. Within the latter, the feed is mixed with recycled material flowing in recycle line 28 and comprising recycled hydrogen introduced from line 30 and recycled alkylnaphthalenes introduced from line 32. Make-up hydrogen in an amount sufficient to compensate for that consumed in the reaction is introduced into recycle hydrogen manifold 30 from line 34. Typically, the hydrocarbon portion of the dealkylation feed will comprise about 65 volume percent of the fresh process feed and about 35 volume percent of recycled alkylnaphthalenes, and about 6000 s.c.f. of hydrogen are provided per barrel of hydrocarbon.

From dealkylation reactor feed manifold 26, the feed mixture passes to preheater 36 wherein it is heated to a temperature of about 900° F., and the heated mixture is then passed via line 38 to dealkylation reactor 10. The latter takes the form of a fire-brick lined shell filled with one-inch alundum balls, and is maintained at a temperature of about 1325° F. and a pressure of about 650 p.s.i.g. The mixture is passed therethrough at such a rate as to maintain a contact time therein of about 10 seconds.

The hot dealkylation reactor effluent passes from reactor 10 to effluent cooler 40 wherein it is cooled to about 140° F., and the cooled and condensed effluent is passed to dealkylate phase separator 12. The normally gaseous components of the dealkylation reactor effluent are withdrawn from separator 12 and are passed via line 42 to gas fractionation means 44 to effect a partial separation of hydrogen and normally gaseous hydrocarbons. The latter are passed to storage via line 46 for use as fuel gas or the like, whereas the fraction enriched in hydrogen (usually to an extent of about 70 to 90 percent) is passed to hydrogen recycle line 30 for return to the dealkylation reactor.

The liquid portion of the dealkylation reactor effluent is passed from separator 12 to fractionation system 14 via transfer line 48, and within the latter is joined by a reformate stream flowing in line 50. Fractionation system 14 (which will usually take the form of several individual distillation columns) is operated to produce an overhead fraction consisting of 400° F. end-point gasoline which is withdrawn from the system via line 52, a naphthalene concentrate fraction boiling over the range 400°-435° F., an alkylnaphthalene fraction boiling over the range 435°-510° F., and a bottoms fraction. The latter is passed to storage via line 54 for use as fuel oil or the like, and the alkylnaphthalene fraction is passed to recycle line 32 for return to dealkylation reactor 10.

The naphthalene concentrate fraction produced in fractionation system 14 is passed via line 56 to naphthalene purification column 16 which is operated to produce, in line 17, a heart-cut fraction distilling at 420°-425° F. and comprising 98.2 percent naphthalene. The overhead fraction, comprising non-naphthalenic materials boiling at 400°-420° F. and a small amount of naphthalene, is passed via line 18 to reformer feed manifold 64. The

bottoms fraction, comprising non-naphthalenic materials boiling at 425°-435° F. and a small amount of naphthalene, is likewise passed from column 16 to reformer feed manifold 64. Within the latter, the non-naphthalenic hydrocarbons are joined by a stream of recycled hydrogen flowing in line 66. Reformer make-up hydrogen is introduced into the system from line 68 in an amount sufficient to provide a total of about 6000 s.c.f. of hydrogen per barrel of hydrocarbon. From manifold 64, the reformer feed mixture passes to preheater 70 wherein it is heated to a temperature of about 800° F., and the heated feed is thence passed to reformer 20.

Reformer 20 is a conventional fixed bed catalytic reactor provided with means for maintaining an average bed temperature of about 950° F. It is operated at a pressure of about 900 p.s.i.g., and a liquid hourly spaced velocity of about 1.25 volumes of hydrocarbon per volume of catalyst per hour. The catalyst consists of 5 weight percent of molybdenum oxide supported on activated alumina.

The effluent from reformer 20 passes to effluent cooler 72, and thence into reformate separator 22 wherein it separates into a liquid phase and gaseous phase. The latter is passed to hydrogen recycle line 66 for return to feed manifold 64, with the net make gas being passed to storage via line 74 for use as fuel. The liquid portion of the reformate, comprising reformate gasoline, naphthalene, alkyl naphthalenes, and a small amount of heavier ends, is introduced into line 59 for transfer to fractionation system 14 and the recovery of these components as individual streams.

Considering now the process of the invention in greater detail, it is adapted to the dealkylation of any petroleum hydrocarbon mixture comprising a substantial amount of alkyl naphthalenes. Catalytically or thermally cracked cycle oils and heavy reformate fractions are most commonly employed, with platinum-catalyzed reformate fractions being particularly preferred.

A particularly preferred process feedstock of this type consists of a platinum-catalyzed reformate fraction boiling between about 435° F. and about 530° F. and comprising 30-90 percent alkyl naphthalenes. A second preferred feedstock consists of a thermally or catalytically cracked cycle oil extract fraction obtained, for example, by subjecting a TCC or FCC cycle oil of suitable boiling range to hydrorefining (i.e., hydrodesulfurization and/or hydrodenitrogenation) in the presence of a cobalt molybdate catalyst (Unifining), and subjecting the hydrorefined product to solvent extraction (e.g., with sulfur dioxide or a glycol) to obtain an extract product rich in naphthalene and naphthalene precursors. Alternatively, the cycle oil can first be solvent extracted and the aromatics-rich extract then hydrorefined to obtain a suitable feedstock. With particularly "clean" cycle oils (i.e., low sulfur and/or low nitrogen) the hydrorefining step can be omitted. Also, when the dealkylation reaction is effected thermally, the pre-removal of sulfur and/or nitrogen from the feedstock need not be complete and in some instances (depending on the sulfur and nitrogen specifications for the naphthalene product) may be omitted entirely.

Since the composition of the product which is subjected to reforming is not substantially dependent on whether the dealkylation reaction is effected catalytically or thermally, the advantages of the process are attained with both types of operation. When carried out catalytically, the reaction is usually effected in the presence of hydrogen, and the catalyst usually comprises an oxide or sulfide of one or more of the metals of groups VIB and VIII of the periodic system supported on an adsorbent carrier. Suitable active components include the oxides and/or sulfides of tungsten, molybdenum, chromium, iron, cobalt, nickel, and mixtures thereof. These active components are supported in minor amounts (e.g., 1-20 weight percent) upon carriers such as alumina, silica, titania, zirconia, zinc oxide, activated clays, and the like, or mixtures thereof. Supports which normally have relatively high cracking activity are preferably deactuated by including

minor amounts of alkalinizing compounds, e.g., sodium oxide, in the catalyst composition. The catalyst may be maintained in the form of a fixed bed, a compact moving bed, or a fluidized bed. Typical catalytic dealkylation conditions include a reaction temperature between about 900° F. and about 1300° F., preferably between about 950° F. and about 1250° F., a reaction pressure between about 700 and about 3000 p.s.i.g., preferably between about 800 and about 1500 p.s.i.g., and a liquid hourly spaced velocity of between about 0.2 and about 5 volumes of hydrocarbon per hour per volume of catalyst. When the reaction is carried out in the presence of hydrogen, as is usually the case, between about 3000 and about 15,000 s.c.f. of hydrogen (usually in the form of a recycle gas containing 70-95 volume percent of hydrogen) are provided per barrel of hydrocarbon. The use of water vapor to moderate the reaction in accordance with the teachings of Doumani, U.S. Patent No. 2,734,929, is a valuable expedient, with the water vapor being provided in an amount representing between about 0.04 and about 0.15 barrel of liquid water per barrel of hydrocarbon. When employing a fixed bed catalyst, it is also desirable to maintain the temperature gradient within the bed at a value below about 100° F. by introducing a hydrogen-containing quench gas into the reaction zone at a plurality of points along the length thereof.

Typical thermal dealkylation conditions include a reaction temperature between about 1000° F. and about 1500° F., preferably between about 1100° F. and about 1350° F., a reaction pressure between about 200 and about 1500 p.s.i.g., and a reaction time of between about 2 and about 20 seconds. Conventionally, thermal dealkylation is likewise carried out in the presence of hydrogen, with between about 2000 and about 10,000 s.c.f. of hydrogen being provided per barrel of hydrocarbon. It is also conventional to effect thermal dealkylation within a fixed, compact moving, or fluidized bed of a non-catalytic inert material, such as sand, pebbles, alundum chips, and the like.

In general, then, the dealkylation reaction may be carried out under any of the wide variety of conditions known to effect the dealkylation of alkyl-substituted hydrocarbons such as alkyl naphthalenes.

The effluent which is withdrawn from the reaction zone is initially treated to separate gaseous from liquid constituents, e.g., by condensation. When hydrogen is employed in the reaction zone it is preferably recovered as a separate gaseous stream for recycle purposes by initially condensing the reactor effluent at an elevated pressure, after which the normally gaseous hydrocarbons (which for the most part have remained dissolved in the liquid hydrocarbon components) are flashed off by reducing the pressure to a substantially lower value, e.g., atmospheric pressure. The remaining liquid components of the reactor effluent are then fractionated.

As previously stated, the fractionation operation is carried out to effect the isolation of the following fractions: (1) a light gasoline fraction (typically having an end-point of about 400° F.) which is taken as a process product, (2) a naphthalene concentrate fraction which is passed to a naphthalene purification operation, (3) a heavy fraction which contains unconverted alkyl naphthalenes and non-naphthalenic hydrocarbons and which is recycled to the dealkylation zone, and (4) a high-boiling fraction which comprises polymeric materials and the like and which is taken as a process product useful as fuel oil or the like. While it is preferred that the naphthalene concentrate fraction be of relatively narrow boiling range, e.g., from about 380° F. to about 450° F., preferably between about 400° F. and about 435° F., and that naphthalene itself be the only naphthalenic component, the process is nonetheless operable should the fractionation operation be carried out so that the naphthalene concentrate contains considerable amounts of alkyl naphthalenes and has an end-boiling point as high as about 500° F.

The naphthalene purification operation, whereby the

naphthalene contained in the naphthalene concentrate fraction is recovered in substantially pure form, can be carried out in a number of ways. When the naphthalene product need be of only nominal purity, e.g., 90-98 percent, such operation may frequently consist merely of a fractional distillation step carried out in the conventional manner. However, in some instances, there are present certain non-naphthalenic materials which form constant boiling mixtures with naphthalene, and in such cases a naphthalene product of even such nominal purity can be obtained only by crystallization, selective solvent extraction of azeotropic distillation. Crystallization is also resorted to when it is required that the naphthalene product have a purity greater than about 98 percent. In recovering naphthalene from the concentrate fraction by crystallization, the operation is carried out in the conventional manner, i.e., by cooling the feed stream to a relatively low temperature to obtain a slurry of naphthalene crystals in mother liquor and thereafter separating the crystals by filtering or centrifuging. Preferably, the cooling is effected in a scraped surface chiller taking the form of a jacketed conduit through which the feed stream is passed. Scrapers adapted to be rotated against the walls of the conduit are provided to prevent crystalline material from building up on the walls of the conduit and interfering with the transfer of heat therethrough. Usually, the jacket is divided into two or more sections through which different refrigerants are circulated at successively lower temperatures. The temperature to which the crystallizer feed stream is cooled and the rate at which such cooling is effected depend on the desired purity of the product and the means and conditions employed for separating the crystals from the mother liquor. In the practice of the present invention I have found it satisfactory to chill the feed to a temperature between about -20° F. and about 0° F., over a period of 30-60 minutes when employing a centrifuge for separating the crystals from the mother liquor. Usually it is desirable to wash the crystals with a light hydrocarbon wash liquid, e.g., pentane, light gasoline, etc., and to remove traces of the wash liquid by steam stripping, distillation, etc.

If necessary, the naphthalene product obtained from the concentrate fraction may be treated with clay or acidic salts in the known manner to remove color bodies. In general, then, in treating the naphthalene concentrate fraction to recover the naphthalene therefrom, any of the techniques and equipment customarily employed in such type of operation may be employed, and any of the known treatments for the purification of petroleum or coal tar naphthalene may be applied.

The reforming step, wherein the non-naphthalenic products obtained from the naphthalene purification operation are treated to form further amounts of naphthalene and alkylnaphthalenes, is carried out as a typical hydroforming operation employing conventional conditions and catalysts. Such conditions comprise: average reaction temperatures between about 825° F. and about 975° F., preferably between about 925° F. and about 975° F., pressures between about 200 and about 800 p.s.i.g., space velocities between about 1.5 and about 5 volumes of hydrocarbon per volume of catalyst per hour, and hydrogen-to-oil ratios of between about 4000 and about 12,000 s.c.f. per barrel. Any conventional reforming catalyst may be used in either fixed bed, compact moving bed, or fluidized bed type of operation. Typical active catalyst components include platinum, palladium, rhodium, molybdenum oxide, vanadium oxide, chrominium oxide, etc., and typical support materials include activated alumina, silica alumina, steam-deactivated silica, etc. A preferred catalyst comprises an activated alumina base containing a minor proportion of fluorine and having between about 0.05 and about 1.0 weight percent of platinum distended thereon. A second preferred type consists of cobalt molybdate (or a mixture of cobalt and molybdenum oxides) supported on activated alumina, bauxite, or other clays,

and prepared as described in U.S. Patent No. 2,687,381.

Treatment of the reformate product to recover the various components thereof as separate entities is substantially the same as that previously described in connection with the dealkylation reactor effluent, i.e., it is condensed to effect separation of normally gaseous and liquid materials, and the latter are fractionated to obtain a light gasoline fraction, a naphthalene concentrate fraction, and one or more heavier fractions. As shown in FIGURE 1, fractionation of the liquid reformate may be carried out simultaneously with the fractionation of the dealkylate. The gaseous portion of the reformer effluent can be employed as such for fuel purposes or, in accordance with more conventional procedure, can be treated to separate at least part of the hydrocarbon components with the remainder being employed to supply part of the required hydrogen.

In the foregoing description of the process of the invention made with reference to FIGURE 1, reforming of the mother liquor was described as an independent operation, i.e., only the non-naphthalenic components of the naphthalene concentrate fraction were fed to the reformer. However, where the process is carried out closely adjacent to reforming facilities normally used for other purposes, such non-naphthalenic components, can simply be passed to such facilities as part of the feed thereto. Thus, in FIGURE 1, reformer 20 can well be a large facility serving primarily to reform naphthenic hydrocarbons, and the non-naphthalenic components of the concentrate fraction will constitute merely a small part of the reforming charge. In such cases, the naphthalene and alkylnaphthalenes produced from the non-naphthalenic components of the concentrate fraction will be recovered along with, and used in the same manner as, the naphthalene and alkylnaphthalenes produced from the naphtha reformer feed. FIGURE 2 shows a preferred embodiment of such type of operation wherein the naphthalene produced by reforming both the non-naphthalenic components of the concentrate fraction and a naphtha is recovered along with the naphthalene produced by dealkylation of the alkylnaphthalenes produced by said reforming.

Referring now to FIGURE 2, the major items of processing equipment there shown include a catalytic reforming reactor 110, reformate phase separator 112, reformate fractionation system 114, dealkylate fractionation system 116, catalytic dealkylation reactor 118, high pressure and low pressure phase separators 120 and 122, respectively, crystallizer 123, and centrifuge 124. The fresh feed, consisting of a straight-run naphtha boiling over the range 50-210° F.-375° F. and having an API gravity of about 45° is introduced into reformer feed manifold 126 and is therein joined by a stream of mother liquor flowing in line 128 and a stream of hydrogen flowing in line 130. About 8000 s.c.f. of hydrogen are provided per barrel of fresh feed and mother liquor. From line 126 the reformer feed mixture passes to feed preheater 132, wherein it is heated to a temperature of about 850° F. and thence into reformer 110.

Reformer 110 is operated at a pressure of about 465 p.s.i.g., and is provided with inter-heaters, not shown, to maintain an average catalyst bed temperature of about 900° F. The catalyst is a conventional platinum reforming catalyst comprising about 1% of platinum supported on alumina and promoted with halogen, and the liquid hourly space velocity is about 1.33 volumes of hydrocarbon per volume of catalyst per hour. The reformer effluent passes from reformer 110 to separator 112 via line 133, and within separator 112 it separates into a hydrogen-rich gaseous phase and a liquid hydrocarbon phase. The gas phase is withdrawn through line 134 and, together with make-up hydrogen introduced from line 136, is passed to line 130 for return to reformer 110. The liquid portion of the reformer effluent is passed from separator 112 via line 138 to reformate fractionation system 114. The latter is operated to produce in line 140 a normally gaseous

fraction comprising C_1 to C_5 hydrocarbons, a heart cut fraction consisting of 385° F. end-point reformate gasoline, and a bottoms fraction comprising higher boiling alkylbenzenes, naphthalene, alkylnaphthalenes, etc.

The bottoms fraction of the reformate is passed from reformate fractionator 114 to dealkylate fractionation system 116 via transfer line 142 wherein it is joined by the liquid portion of the dealkylator effluent flowing in line 144. As is apparent, dealkylate fractionation system 116 serves the dual purpose of fractionating the dealkylated product and effecting further fractionation of the reformate bottoms fraction. It is operated to produce an overhead fraction of 400° F. end-point dealkylate gasoline in line 146, a naphthalene concentrate fraction (B.R.=400°-430° F.) in line 148, an alkylnaphthalene fraction (B.R.=430°-540° F.) in line 150, and a bottoms fraction in line 152. The latter fraction is passed to storage for use as fuel oil or the like.

The naphthalene concentrate fraction flowing in line 148 is passed to crystallizer 123, which takes the form of a scraped surface chiller, wherein it is chilled to a temperature of about -10° F. over a period of about 45 minutes. The slurry of naphthalene crystals in mother liquor which is thereby formed is passed to centrifuge 124 to effect separation of the two phases; crystals of essentially pure naphthalene (melting point=80° C.) are passed to storage via line 154, and the mother liquor comprising non-naphthalenic components of the naphthalene concentrate fraction produced in line 148 is introduced into line 128 for return to reformer 110.

The alkylnaphthalene fraction flowing in line 150 constitutes the hydrocarbon feed to the dealkylation step. Said feed, together with water and hydrogen flowing in lines 156 and 158, respectively, is passed to preheater 160 wherein it is heated to an incipient reaction temperature, and the preheated mixture is passed to dealkylation reactor 118. About 8100 s.c.f. of hydrogen and about 0.085 barrel of water are provided per barrel of hydrocarbon in the reactor feed mixture, and the mixture is passed to reactor 118 at such rate that the liquid hourly space velocity within the reactor is about 0.4 volume of hydrocarbon per volume of catalyst per hour.

¹ Assuming 100% recovery of naphthalene, and 100% conversion (by dealkylation) of all alkylnaphthalenes to naphthalene.

Reactor 118 contains a fixed bed of a dealkylation catalyst consisting of a silica-stabilized alumina base having supported thereon about 3.0 weight percent of cobalt oxide, about 9.0 weight percent of molybdenum oxide, and about 2.2 weight percent of sodium oxide. The reaction zone is maintained at a temperature of about 1150° F. and a pressure of about 1000 p.s.i.g., and a substantially uniform temperature profile within the catalyst bed is maintained by introducing a quench gas consisting of part of the hydrogen-containing recycle gas flowing in line 162 into the reaction zone at a plurality of points along the length thereof via lines 164. About 1430 s.c.f. of quench gas are employed per barrel of hydrocarbon in the reactor feed.

The dealkylation reactor effluent passes from reactor 118 to high pressure separator 120 which is operated at

a pressure only slightly below that of reactor 118. Within separator 120, the effluent separates into a gaseous phase, a liquid-hydrocarbon phase, and an aqueous phase. The latter is withdrawn via line 166 and is either discarded or recycled back to the reactor via line 156. The gaseous phase, which comprises hydrogen and a relatively small amount of normally gaseous hydrocarbons, is withdrawn from separator 120 and is passed to line 162 for use as the reactor quench gas and for recycle to reactor 118 via line 158. Make-up hydrogen is introduced into the system from line 168. The liquid hydrocarbon phase in separator 120 is withdrawn therefrom and is passed through pressure relief valve 170 into low pressure separator 122 which is operated at a near atmospheric pressure. Within separator 122 the dissolved normally gaseous hydrocarbons flash off to form a gaseous phase which is withdrawn and passed via line 172 to storage for use as fuel gas or the like. The liquid hydrocarbon phase which forms in separator 122 is passed to line 144 for transfer to fractionation system 116 and recovery of the naphthalene product.

The following table presents data which indicate quantitatively the results obtained by the process of the invention. These data were obtained by reforming a series of blends prepared by mixing varying quantities of crystallizer mother liquor with a typical reformer feed naptha, and thereafter analyzing the 390° F.+ fraction of the reformate for naphthalene and C_{11} and higher alkyl-naphthalenes. The mother liquor was one obtained by catalytically dealkylating a 430°-500° F. reformate fraction under the conditions and with the catalyst previously described in connection with the dealkylation step of the process illustrated by FIGURE 2, and thereafter crystallizing naphthalene from a 405°-430° F. fraction of the dealkylate. The reformer feed with which the mother liquor was blended was a desulfurized straight-run naptha boiling at 300°-380° F., and the reformer was operated at an average bed temperature of about 905° F., a pressure of about 465 p.s.i.g., a hydrogen-to-oil ratio of about 10,000 s.c.f. per barrel of hydrocarbon, and at a liquid hourly space velocity of 1.32 volumes of hydrocarbon per volume of catalyst per hour.

ployed, provided the step or steps stated by any of the following claims, or the equivalent of such stated step or steps, be employed.

I, therefore, particularly point out and distinctly claim as my invention:

1. In a process wherein an alkylnaphthalene is subjected to dealkylating conditions to obtain a naphthalene-containing product, and said product is thereafter separated into a first fraction rich in naphthalene and a second fraction lean in naphthalene, the method of forming further amounts of naphthalenic hydrocarbons which comprises subjecting said second fraction to reforming conditions.

2. In a process wherein an alkylnaphthalene-containing feedstock is subjected to dealkylating conditions in the presence of added free hydrogen to obtain a naphthalene-containing product, said product is fractionated to obtain a naphthalene concentrate fraction boiling within the range of about 380° F. to about 500° F., and said fraction is treated to separate naphthalene therefrom, the method of forming further amounts of naphthalenic hydrocarbons which comprises subjecting the remainder of said fraction to reforming conditions in the presence of added free hydrogen.

3. In a process wherein a petroleum naphtha is passed through a reforming zone and is therein contacted with a catalyst in the presence of added free hydrogen and under reforming conditions of temperature and pressure to form a reformate product containing alkylnaphthalenes, said reformate product is fractionated to obtain a fraction rich in said alkylnaphthalenes, said alkylnaphthalene-rich fraction is subjected to dealkylating conditions in the presence of added free hydrogen to form a dealkylate product containing naphthalene, said dealkylate product is fractionated to obtain a fraction rich in naphthalene but also containing non-naphthalenic hydrocarbons, and said naphthalene-rich fraction is treated to separate naphthalene therefrom, the method of increasing the proportion of naphthalenic hydrocarbons in said reformate product which comprises returning to said reforming zone at least a portion of the non-naphthalenic components of said naphthalene-rich fraction.

4. A process as defined by claim 3 wherein said naphthalene-rich fraction boils within the range of about 400° F. to about 450° F., and is subjected to crystallization to separate naphthalene therefrom, and said non-naphthalenic components are returned to said reforming zone in the form of the mother liquor from said crystallization.

5. A process as defined by claim 3 wherein said naphthalene-rich fraction boils within the range of about 400° F. to about 435° F. and is subjected to fractional distillation to separate naphthalene therefrom.

6. A process as defined by claim 3 wherein said reforming catalyst comprises platinum supported on alumina, and said alkylnaphthalene-rich fraction is subjected to said dealkylating conditions in the presence of a dealkylation catalyst comprising a compound selected from the class consisting of the oxides and sulfides of the metals of groups VIB and VIII of the periodic system distended on a catalyst support comprising alumina.

7. The process for preparing naphthalene which comprises subjecting an alkylnaphthalene-containing feedstock to dealkylating conditions in the presence of added free hydrogen to obtain a dealkylate product containing naphthalene derived from the alkylnaphthalenes contained in said feedstock; fractionally distilling said dealkylate product to obtain a fraction containing said naphthalene in admixture with non-naphthalenic components of said dealkylate product; treating said fraction to separate said naphthalene from said non-naphthalenic components; and subjecting at least a portion of the separated non-naphthalenic components to reforming conditions in the presence of free hydrogen.

8. A process as defined by claim 7 wherein said frac-

tion boils within the range of about 400° F. to about 450° F. and is subjected to crystallization to separate said naphthalene from said non-naphthalenic components, and said separated non-naphthalenic components are subjected to said reforming conditions in the form of the mother liquor from said crystallization.

9. A process as defined by claim 7 wherein said feedstock is a reformate fraction having an initial boiling point about 430° F., said fraction boils within the range of about 400° F. to about 450° F. and is subjected to fractional distillation to separate said naphthalene from said non-naphthalenic components.

10. A process as defined by claim 7 wherein said alkylnaphthalene-containing feedstock is subjected to said dealkylating conditions in the absence of a dealkylation catalyst.

11. A process as defined by claim 7 wherein said alkylnaphthalene-containing feedstock is subjected to said dealkylating conditions in the presence of a dealkylation catalyst comprising a compound selected from the class consisting of the oxides and sulfides of the metals of group VIB and VIII distended on a catalyst support comprising alumina.

12. A process as defined by claim 11 wherein said catalyst comprises a mixture of the oxides of cobalt and molybdenum distended on a support comprising a major proportion of alumina and minor proportions of silica and an alkali, and the dealkylation reaction is carried out in the presence of water vapor.

13. A process as defined by claim 7 wherein said non-naphthalenic components are subjected to said reforming conditions in admixture with a petroleum naphtha.

14. A process as defined by claim 7 wherein said separated non-naphthalenic components are subjected to said reforming conditions in the presence of a reforming catalyst comprising platinum supported on alumina.

15. The process for preparing naphthalene which comprises: (1) introducing a petroleum naphtha into a reforming zone and therein contacting it with a reforming catalyst under reforming conditions and in the presence of added free hydrogen; (2) withdrawing from said reforming zone a reformate product comprising naphthalene and alkylnaphthalenes; (3) fractionally distilling said reformate product to separate a reformate fraction containing said naphthalene and alkylnaphthalenes and non-naphthalenic hydrocarbons of the same boiling range; (4) admixing said fraction with the hereinafter identified recycle stream; (5) fractionally distilling the resulting mixture to obtain a first fraction rich in naphthalene and containing non-naphthalenic hydrocarbons, and a second fraction rich in alkylnaphthalenes; (6) separating naphthalene from the non-naphthalenic hydrocarbon components of said first fraction; (7) introducing at least a portion of the separated non-naphthalenic hydrocarbon components into said reforming zone; (8) introducing said second fraction into a dealkylation zone and therein subjecting it to dealkylating conditions in the presence of added free hydrogen; (9) withdrawing from said dealkylation zone a dealkylate product comprising naphthalene and alkylnaphthalenes; and (10) returning to step (4) as said recycle stream a naphthalene- and alkylnaphthalene-containing portion of said dealkylate product.

16. A process as defined by claim 15 wherein, in step (6), said naphthalene is separated from said non-naphthalenic hydrocarbon components by subjecting said first fraction to crystallization; and, in step (7), said separated non-naphthalenic hydrocarbon components are introduced into said reforming zone in the form of the mother liquor obtained in said crystallization.

17. A process as defined by claim 15 wherein, in step (8), said second fraction is subjected to said dealkylating conditions in the presence of added water vapor and a dealkylation catalyst comprising a compound selected from the class consisting of the oxides and sulfides of the metals of group VIB and VIII distended on a sup-

port comprising a major proportion of alumina and minor proportions of silica and an alkali.

18. A process as defined by claim 15 wherein, in step (1), said reforming catalyst comprises platinum supported on alumina.

19. A process as defined by claim 15 wherein, in step (8), said second fraction is subjected to said dealkylating conditions in the absence of a dealkylation catalyst.

20. A process as defined by claim 17 wherein, in step (1), said reforming catalyst comprises platinum supported on alumina; in step (3) said reformate fraction boils above about 385° F.; in step (5) said first fraction boils within the range of about 400° F. to about 435° F., and said second fraction boils within the range of about 435°

F. and about 540° F.; and in step (8) said second fraction is subjected to said dealkylating conditions in the presence of added water vapor and a dealkylation catalyst comprising the oxides of cobalt and molybdenum distended on a support comprising a major proportion of alumina and minor proportions of silica and an alkali-metal alkali.

UNITED STATES PATENT OFFICE
CERTIFICATE OF CORRECTION

Patent No. 3,193,594

July 6, 1965

Hibbard R. Emmerson

It is hereby certified that error appears in the above numbered patent requiring correction and that the said Letters Patent should read as corrected below.

Column 9, line 43, for "cldaim" read -- claim --; column 10, line 9, after "point" insert -- above --; column 10, line 41, for "withdrawings" read -- withdrawing --.

Signed and sealed this 21st day of December 1965.
